Werner H. Stemmer; Ralph E. Locher(57) **CLAIM**

The ornamental design for a food product in the shape of a UFO, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a food product in the shape of a UFO, showing my new design;

FIG. 2 is a top plan view thereof;

FIG. 3 is a bottom plan view thereof; and,

FIG. 4 is a cross-sectional view thereof, taken along line IV-IV in FIG. 3.

1 Claim, 4 Drawing Sheets
